UNITED STATES PATENT OFFICE.

WILLIAM L. GARLAND, OF LLANERCH, PENNSYLVANIA, ASSIGNOR TO THE SAFETY CAR HEATING & LIGHTING COMPANY, A CORPORATION OF NEW JERSEY.

CAR-HEATING SYSTEM.

1,032,398.

Specification of Letters Patent.

Patented July 16, 1912.

Application filed June 11, 1909. Serial No. 501,502.

To all whom it may concern:

Be it known that I, WILLIAM L. GARLAND, a citizen of the United States, residing at Llanerch, in the county of Delaware and State of Pennsylvania, have invented certain new and useful Improvements in Car-Heating Systems, of which the following is a full, clear, and exact description, such as will enable others skilled in the art to which 10 it appertains to make and use the same.

This invention relates to heating systems and more especially to systems installed in metal cars.

One of the objects is to provide a practical system of this character in which the metallic wall of the car will be positively heated.

Another object is to provide a system in which the air contained within the space 20 between the outer and inner sheathings will be heated.

Further objects are to provide a system of this character which will be inexpensive and simple in its construction; which may 25 be readily installed in cars without requiring any alteration in their construction; and which will be efficient in use.

Other objects will be in part obvious and in part pointed out hereinafter.

The invention accordingly consists in the features of construction, combinations of elements and arrangement of parts which will be exemplified in the construction herein- 30 after set forth, and the scope of the application of which will be indicated in the following claims.

In the accompanying drawings, wherein is shown one of various possible embodiments of the invention, Figure 1 is a dia- 40 grammatic perspective view illustrating the location of the heating system with respect to the floor of the car body; Fig. 2 is a vertical, sectional view of a portion of a car; Fig. 3 is a plan view of Fig. 2; Fig. 4 is an enlarged sectional view taken on the line $x-x$ of Fig. 2.

As tending to a more ready understanding of certain features and aims of this invention, it may here be noted that in cars constructed of metal it has been found that in cold weather the inner sheathing of the side walls is likely to be cold, due, largely, to the heat conducting powers of metal, even though the interior of the car is comfortably heated. The window sills, also,

are likely to be cold, and passengers seated next the windows are thus often uncomfortably cold, due to the proximity of these chilled surfaces. The above objections and others are obviated by means of the system 60 hereinafter described.

Referring now to the drawings, 1 indicates the flooring of the car body and 2 and 3 indicate the outer and inner sheathing, respectively, of one of the side walls, the 65 window-sill being shown at 4.

5 indicates car seats of any approved construction, one of which is preferably positioned adjacent each window, as usual in car construction.

A train pipe 6 adapted to be connected to a source of heated medium, such as the steam from a locomotive, extends lengthwise of the car as is usual in train heating systems, and is connected by a branch pipe 75 7 to a suitable radiator 8 which, in the present instance, is represented as consisting of piping extending preferably from the center of the car toward each end thereof, and returning to a pipe 9 which communicates 80 with a suitable steam-trap 10. A valve 11 preferably located in the branch pipe 7 regulates the flow of the heated medium to the radiating system. The radiating pipes 8 are placed adjacent the inner sheathing of 85 the car wall, as clearly indicated in Fig. 4, being preferably arranged with the portion which is connected to the source of supply above the portion which communicates with the steam-trap.

At different points of the radiating system, preferably between each of the seats as indicated in Figs. 2 and 3, a heat conducting member such, for example, as a large metal block 12, is positioned between the 95 upper pipe of the radiator and the inner sheathing of the wall, being in intimate contact with each of these members. As shown in Fig. 4 the block is preferably recessed as at 13 to receive the piping of the radiating system, and the parts may be maintained in position in any suitable manner, as, for example, by means of a strap 14 secured in position by suitable fastening means 15, such as screws, which extend 105 through the block 12 and through the inner sheathing 3, as indicated in Fig. 4. It will, of course, be understood that any other suitable heat-conducting member could be employed in place of the block and that any 110

other suitable fastening means could be utilized, although many advantages reside in the form shown.

The operation of the system, which should 5 be largely obvious from the above description, is as follows: When the steam is admitted into the radiator, the conduits through which it flows will become heated. This heat will not only be radiated there- 10 from to warm the air within the car, but will be communicated by conduction through the blocks 12 to heat also the inner sheathing 3 of the wall, through which it will be conducted to the sills of the windows, 15 thus insuring that these portions of the car will be positively heated. It will also be understood that the air contained between the inner and outer sheathing will be warmed, thus assisting in attaining the de- 20 sired object.

It will thus be seen that the objections above-noted are fully overcome by means of the system herein described. It will also be seen that the apparatus may be installed in 25 any car without the necessity of altering the same to any appreciable extent, and that the system will be simple in construction and efficient in operation.

As many changes could be made in the 30 above construction and many apparently widely different embodiments of this invention could be made without departing from the scope thereof, it is intended that all matter contained in the above descrip- 35 tion or shown in the accompanying drawings shall be interpreted as illustrative and not in a limiting sense. It is also to be understood that the language used in the following claims is intended to cover all of 40 the generic and specific features of the invention herein described, and all statements of the scope of the invention which, as a matter of language, might be said to fall therebetween.

45 Having described my invention, what I claim as new and desire to secure by Letters Patent, is:

50 1. In a heating system, in combination with a passenger car body having a metallic inner wall, of a plurality of seats within said car, a conduit within the car adapted to be connected to a source of supply of heated medium through which said medium is

adapted to flow, and a plurality of metallic blocks one between each pair of the seats of 55 said car connected with the wall and said conduit whereby heat is conducted from one to the other.

2. In a heating system, the combination with a car body having an inner metallic 60 sheathing, of a conduit within the car adapted to be connected to a source of supply of a heated medium and through which said medium is adapted to flow, a return conduit substantially parallel thereto, and a metallic 65 member fitted between and in contact with said first mentioned conduit only and said sheathing.

3. In a heating system, the combination, with a metallic car body provided with a 70 window in one of its walls, of a window-sill associated therewith, a conduit within said car adapted to be connected to a source of supply of a heated medium, and intermediate means comprising a relatively large 75 block of heat conducting material secured thereto between said conduit and window-sill whereby heat is transmitted from one to the other by conduction.

4. In a heating system, the combination 80 with a car body provided with a window in one of its walls, of a window sill associated therewith, a conduit within the car adapted to be connected to a source of supply of a heated medium and through which said medium is adapted to flow, and metallic means 85 operatively associated with said conduit and the wall of the car adjacent said sill for causing the sill to be heated by the medium flowing through the conduit.

90 5. In a heating system, the combination with a car body provided with a plurality of windows in one of its walls, a window sill associated with each of said windows, a conduit within the car adapted to be connected 95 to a source of supply of a heated medium and through which said medium is adapted to flow, and metallic means interposed between said conduit and said wall adjacent each of said windows.

100 In testimony whereof I affix my signature, in the presence of two witnesses.

WILLIAM L. GARLAND.
